UNITED STATES PATENT OFFICE

164,823

TELEVISION LAMP OR SIMILAR ARTICLE

Mario Russo, New Rochelle, N. Y.

Application May 23, 1951, Serial No. 15,289

Term of patent 3½ years

(Cl. D48—20)

To all whom it may concern:

Be it known that I, Mario Russo, a citizen of the United States, and a resident of New Rochelle, N. Y., have invented a new, original, and ornamental Design for a Television Lamp or Similar Article, of which the following is a specification, reference being had to the accompanying drawing, forming a part hereof, in which

Figure 1 is a rear perspective view of a television lamp or similar article, showing my new design;

I claim:

The ornamental design for a television lamp or similar article, as shown.

MARIO RUSSO.
